DESIGN FOR A LADY'S NIGHTGOWN

Paul J. Balog, North Hollywood, Calif.

Application March 6, 1948, Serial No. 144,941

Term of patent 7 years

(Cl. D3—26)

To all whom it may concern:

Be it known that I, Paul J. Balog, a citizen of the United States, residing at North Hollywood, California, in the county of Los Angeles and the State of California, have invented a new, original, and ornamental Design for a Lady's Nightgown, of which the following is a specification, reference being had to the accompanying drawing, forming a part thereof.

I claim:

The ornamental design for a lady's nightgown, as shown.

PAUL J. BALOG.
